ATTORNEY

UNITED STATES PATENT OFFICE.

VLADIMIR B. SOUNITZA, OF NEW YORK, N. Y.

OIL FURNACE.

Application filed February 25, 1925. Serial No. 11,473.

To all whom it may concern:

Be it known that I, VLADIMIR B. SOUNITZA, citizen of Russia, and resident of New York city, in the county of New York, and State of New York, have invented certain new and useful Improvements in Oil Furnaces, of which the following is a specification.

My invention relates to oil furnaces and has a particular reference to furnaces of a rotating type, employing means for gasifying oil before it is burned in the furnace.

The object of my invention is to provide a furnace in which the highest economy may be obtained by burning a mixture of pre-heated air with hot gases, the latter being prepared in special chambers in connection with my furnace.

My invention is more fully described in the accompanying specification and drawing in which—

Fig. 1 is a sectional elevation of my furnace. Fig. 2 is an end view taken in section on the line 2—2, Fig. 1.

My furnace consists of a combustion chamber 1 lined with refractory material 2 inside and enclosed in a metal shell or housing 3. Vents 4 are provided on top for the exhaust gases and a pouring nozzle 5, normally closed with a plug 6 with a metal cap 7.

The furnace is made in the form of an elongated cylindrical container, with cylindrical apertures 8 at both ends and with expanded central portion for the material to be melted, such as iron, glass etc. Metal cylinders 9 are attached to the ends of the central shell 3 with flanges 10 (bolts 11 or rivets). These cylinders are provided with circular races 12 for the rollers 13 assembled on retaining rings 14. These rollers are supported on semicircular stationary races 15 on standards 16. The races are provided with flanges 17 and 18 in order to retain the rollers in position.

A gear sector 19 is attached to the ring or cylinder 9 and is in mesh with a pinion 20 on a shaft 21 journaled in the standard 16. A sprocket 22 is mounted on the end of the shaft and is connected with another sprocket

23 by means of a chain 24. The sprocket 23 is rotated by an electric motor (not shown). Triggers or dogs 25 are attached to the chain at predetermined positions, so that the chain reverses its movement every time the dog 55 throws the switch 26 over, thereby reversing the rotation of the driving motor.

The connections between the reversing switch and the motor are not shown, as they can be made by anyone skilled in the art of connecting electric motors, by some well known scheme.

The dogs are placed in such positions, that the furnace can be tilted on both sides only about 90 degrees from the central vertical 65 position, as shown with dotted lines, positions II and III.

The switch 26 is placed rotatively in a horizontal direction on a pin 27, so that it can be moved out of the engagement with the 70 chain dogs so as to be operated manually.

The ends of the furnace are provided with recesses 28 fitting with slight clearances over cylindrical chambers 29. These chambers are made in the form of metal shells or housings 30 supported on standards 16 and lined inside with refractory material 31 which forms walls separating the chambers from the combustion chamber 1. Inclined ducts 32 are provided in these separating walls for 75 the gases, these ducts being adapted to direct the flame down towards the lowest point of the furnace, where the opposite flames meet together and become deflected upwards and to the rear towards the exhaust 80 ports 4.

The rear walls of the chambers 29 are provided with ports 33 normally closed with plugs 34.

The air is brought into the gasifying 85 chambers 29 through pipes 35 which are divided into branches 36 connecting with oval apertures 37 in the lining 31. These apertures or ports 37 are made at an angle, as shown in Fig. 2, so that the air enters tangentially to the inner periphery of the chamber.

The fuel oil is fed into the chambers 29 through fuel pipes 38 terminating outside 900 with funnels 39 through which the oil may

be fed into these pipes from any suitable source. The pipes are provided with portions bent down in the shape of the letter U, forming liquid traps so as to prevent the oil being blown backwards by the pressure of gases. 5

The pipes 35 may be provided with butterfly valves 40 in order to control the amount of air admitted into the furnace.

10 The operation of my furnace is as follows:

Material to be melted is placed in the furnace through the port 5. The gas generating chambers 29 are then heated by burning 15 some suitable fuel, such as wood, coal, etc., until the walls become hot. The oil is then begun to be fed into the pipes 38 through funnels 39, and at the same time an air blast is started through pipes 35. The oil 20 is drawn from the pipes by the air and whirled around in the generating chambers in a contact with the heated walls. A partial combustion of the oil will raise the temperature and maintain it at a certain level, 25 sufficient to decompose the oil and to evaporate it, forming combustible gases and vapors, at the same time heating the excess of air.

30 The hot mixture of gases and of the air will be then blown inside of the furnace through ports 32 in the walls separating the generating chambers from the combustion chamber of the furnace. The gases follow the path of the arrows 41, meeting in the 35 center at the bottom of the furnace, rising together to the top, and turning around towards the exhaust ports 4.

35 The burning gases, therefore, are compelled to describe a long path, sufficient to produce a complete combustion, at the same time thoroughly washing the inside portions of the furnace and heating the material.

40 When the melting begins, the furnace may be set into rotation back and forth on its 45 bearings 13 so as to allow the thorough mixing of the melted material.

45 When melting iron the lining of the furnace may be made of a suitable material, such as silica, so as to produce a beneficial 50 effect on the iron, and I have found that an iron scrap of very poor quality can be converted into a good grade of a soft gray cast iron in my furnace, by this process of oscillating the furnace and bringing the melted iron continuously in contact with fresh 55 portions of the reducing lining, thereby converting the hard pearlite of it into graphite.

60 Important advantages of my furnace are that it can burn any kind of liquid fuel with a high efficiency, producing high temperature, sufficient to melt all ordinary metals, including iron, and glass, also that it can improve the quality of gray iron, and is simple and convenient to handle.

65 Another advantage is that the flames fol-

low a long path in comparison to the length of the combustion chamber, so that a very complete combustion is accomplished (the flame from each gas producing chamber being doubled up back on itself). 70

I claim as my invention:

1. In an oil furnace, the combination with a combustion chamber, gas generating chambers at the opposite ends of said combustion chamber, wall separating said gas generating chambers from said combustion chambers, said walls being provided with apertures for the gases, said apertures being adapted to direct the gas flames towards the lower portion of said combustion chamber 80 near its center, exhaust ports in said combustion chamber adapted to receive the products of combustion on their return path from the central portion of said combustion chamber, and means to introduce a liquid fuel into said gas producing chambers. 85

2. In an oil furnace, the combination with a combustion chamber, gas producing chambers at the ends of said combustion chamber, walls separating said gas chambers from said combustion chamber, said walls being provided with apertures for the gases, said apertures being adapted to direct the flame from said gas apertures towards central portion of said combustion chamber, ports in 90 said combustion chamber adapted to receive the products of combustion on their return path from the central portion of said combustion chamber, means to introduce air into said gas chambers, and means to introduce 100 oil into said gas chambers.

3. In an oil furnace, the combination with a combustion chamber, gas producing chambers at the ends of said combustion chamber, walls separating said gas chambers from said combustion chamber, said walls being provided with apertures for the gases, 105 means to introduce liquid fuel into said gas producing chambers, pipes adapted to deliver air to said gas chambers, the walls of 110 said gas chambers being provided with apertures connected with said air pipes, said apertures being directed at an angle with the axis of said gas chambers and adapted to cause the rotative movement of the air in 115 said gas chambers.

4. In an oil furnace, the combination with a tubular combustion chamber, the ends of said chamber being open, gas producing chambers in a cooperative relation with said combustion chamber, the walls of said gas chambers separating said gas chambers from said combustion chamber, said walls being provided with apertures for the gases, said apertures being adapted to direct the flame 120 towards the middle portion of said furnace, said combustion chamber being of a larger diameter in the middle than at the ends, a charging port in the middle portion of said combustion chamber, means to rigidly sup- 125

port said gas chambers, means to introduce air into said gas chambers, means to impart rotative movement to said air inside of said gas chambers, means to introduce liquid fuel in the path of said air in said gas chambers, means to rotatively support said combustion chamber, and means to automatically limit the rotative movements of said combustion chamber, said furnace being adapted to be rotated while in operation.

5. In an oil furnace, the combination with a cylindrical combustion chamber, a spout on said chamber, exhaust ports on said chamber, said spout and said exhaust ports being arranged on the cylindrical portion of said chamber, means to rotatively support said chamber, gas generating chambers adjacent to the open ends of said combustion chamber, walls separating said gas generating chambers from said combustion chamber, said walls being provided with narrow apertures for the gases, and means to in-

10 troduce air and fuel into said gas generating chambers.

6. In an oil furnace, the combination with a combustion chamber, the central portion of said chamber being of a larger cross section than its end portions, the end portions being provided with large apertures, means to rotatively support said chamber, a spout in the middle portion of said chamber, gas generating chambers adjacent to the open ends of said combustion chamber, walls in said gas chambers separating them from said combustion chamber, said walls being provided with narrow apertures, means to support said gas generating chambers and means to introduce air and fuel into said gas chambers.

15 Signed at New York in the county of New York and State of New York February A. D. 1925.

20 VLADIMIR B. SOUNITZA.
